(57) **CLAIM**

The ornamental design for a cigar holder, as shown and described.

DESCRIPTION

FIG. 1 is a rear perspective view of a cigar holder with a cigar placed in one possible position on the cigar holder; FIG. 2 is a left perspective view thereof; FIG. 3 is a right perspective view thereof; FIG. 4 is a front perspective view thereof; FIG. 5 is a front view thereof; FIG. 6 is a left view thereof; FIG. 7 is a right view thereof; FIG. 8 is a rear view thereof;

FIG. 9 is a bottom view thereof; and, FIG. 10 is a top view thereof. The broken lines in the drawings illustrate environmental subject matter and form no part of the claimed design.
